(57) CLAIM

I claim the ornamental design for a dental floss dispenser, as shown and described.

DESCRIPTION

FIG. 1 is a back view of the dental floss dispenser.

FIG. 2 is a bottom view of the dental floss dispenser.

FIG. 3 is a front view of the dental floss dispenser.

FIG. 4 is a view from one side of the dental floss dispenser (the view from the other side corresponds); and,

FIG. 5 is a top view of the dental floss dispenser.
